US00D962976S

(12) **United States Design Patent** (10) Patent No.: **US D962,976 S**
Baker et al. (45) Date of Patent: **** Sep. 6, 2022**

(54) **DISPLAY SCREEN OR PORTION THEREOF WITH GRAPHICAL USER INTERFACE**

(71) Applicant: **Beckman Coulter, Inc.**, Brea, CA (US)

(72) Inventors: **Brittany R. Baker**, Arlington, MN (US); **Daniel Sunoh Choe**, Minneapolis, MN (US); **Andrew Cottrell**, Minneapolis, MN (US); **Dana Vajen Habig**, Cincinnati, OH (US); **Tony J. Riley**, Minneapolis, MN (US); **Mindie Seh-wha Te**, Fullerton, CA (US); **XiaoYin Wang**, Suzhou (CN); **Chad M. Weber**, Shakopee, MN (US)

(73) Assignee: **Beckman Coulter, Inc.**, Brea, CA (US)

(**) Term: **15 Years**

(21) Appl. No.: **29/800,096**

(22) Filed: **Jul. 19, 2021**

CLAIM

The ornamental design for a display screen or portion thereof with graphical user interface, as shown and described.

DESCRIPTION

FIG. 1 is a front view of a first embodiment of a display screen or portion thereof with graphical user interface; FIG. 2 is a front view of a second embodiment thereof; FIG. 3 is a front view of a third embodiment thereof; FIG. 4 is a front view of a fourth embodiment thereof; and, FIG. 5 is a front view of a fifth embodiment thereof. The outermost dot-dash broken lines in the drawings illustrate a display screen or portion thereof that forms no part of the claimed design. The remaining dashed broken lines in the drawings illustrate portions of the graphical user interface that form no part of the claimed design.

1 Claim, 5 Drawing Sheets
